CONTROL KNOB

Robert B. Heckman, Fort Atkinson, Wis., assignor to Thomas Industries, Inc., Fort Atkinson, Wis., a corporation of Delaware

Filed Jan. 26, 1959, Ser. No. 54,319

Term of patent 14 years

(Cl. D26—13)

FIG. 1

FIG. 2

FIG. 3

FIG. 4

Fig. 1 is a front elevation of the control knob, showing my new design;

Fig. 2 is a side elevation thereof;

Fig. 3 is a rear elevation thereof; and

Fig. 4 is a perspective view thereof.

The switch plate shown in broken lines in Fig. 1 is for illustrative purposes only.

The serrations are continuous around the side of the knob as indicated by dot-dash lines in Fig. 1.

I claim:

The ornamental design for a control knob, substantially as shown and described.
